UNITED STATES PATENT OFFICE.

JOSEPH KINTZ, OF WEST MERIDEN, CONNECTICUT, ASSIGNOR TO HIMSELF
AND P. J. CLARK, OF SAME PLACE.

IMPROVEMENT IN THE PROCESSES OF COLORING TIN, ZINC, &c., SO AS TO RESEMBLE GILDING.

Specification forming part of Letters Patent No. 129,284, dated July 16, 1872.

Specification describing a new and Improved Process for Coloring Tin, Zinc, &c., invented by JOSEPH KINTZ, of West Meriden, in the county of New Haven and State of Connecticut.

My invention consists of an improved process for coloring tin, zinc, or any similar metal, which is as follows: I coat such metals with copper and polish them, and lacquer the polished surfaces, and thus produce a bright and permanent color of polished brass; or I may polish the metal to be colored before coppering and produce a similar result, though not quite as good.

Having thus described my invention, I claim as new and desire to secure by Letters Patent—

The method of producing a fine gilt-finish on zinc, tin, or analogous metals by polishing the metal between the coppering and lacquering processes, as described, whereby the same effect is produced as by a gold-gilding, and at less than one-fifth of the cost.

JOSEPH KINTZ.
